UNITED STATES PATENT OFFICE.

HENRY T. PLEINES, OF CLEVELAND, OHIO, ASSIGNOR TO THE LAKWOOD ENGINEERING COMPANY, OF LAKWOOD, OHIO, A CORPORATION OF OHIO.

INDUSTRIAL TRUCK.

Application filed May 9, 1919. Serial No. 295,981.

To all whom it may concern:

Be it known that I, HENRY T. PLEINES, a citizen of the United States, residing at Cleveland, in the county of Cuyahoga and State of Ohio, have invented a certain new and useful Improvement in Industrial Trucks, of which the following is a full, clear, and exact description.

The present invention relates to that type of trucks which are commercially known as industrial trucks.

In this type of trucks it is quite common to provide the trucks with a platform which may be raised to a limited extent, either by hand power or motor power and the truck of the present invention embodies a similar feature but additionally provides a construction and mechanism by which the platform may be raised to a considerably greater height than the usual type of lifting trucks, so that material which is being carried by the truck may be elevated to any height desired within the limits of the truck, thus enabling the truck to be utilized not only as a lifting truck, but as a tiering truck as well.

The objects of the invention are manifold. One object is to provide a self propelled truck which may be used as a lifting truck and as a tiering truck.

A further object is to provide a construction in which the raising and lowering operation of the lifting platform portion of the truck is also controlled, so as to be stopped at the limit of its movement.

A further object is to provide a construction such that when the lifting platform is elevated beyond a predetermined height above the floor level, the electric circuit which includes the driving motor for the truck, is opened, thereby making it impossible to drive the truck wheels while the lifting platform is being moved.

A further object is to provide construction wherein the platform is raised or lowered by a mechanism which automatically becomes locked when the driving power for raising the platform is stopped, so that the platform is held in position and at the height to which it has been raised.

Further objects of the invention will appear more at large as the description proceeds and generally speaking the invention

may be said to comprise the elements and the combination thereof set forth in the accompanying claims.

Reference should be had to the accompanying drawings forming a part of this specification in which Fig. 1 is a side elevation of the truck embodying my invention; Fig. 2 is a top plan view; Fig. 3 is a front elevation; Fig. 4 is a top plan view with portions broken away from a part of the driving mechanism; Fig. 5 is a side elevation with portions in section showing certain features of the construction for the mounting of the lifting platform; Fig. 6 is a diagram of an electric circuit.

Referring to the drawings, the frame of the truck comprises a forward portion which is made up of lower side members 1, and upper members 2, these side members at their forward ends are connected with transversely extending members 3 and the upper and lower members 1 at their forward portions are connected to each other by means of members 4.

The members 1 are preferably made of channel iron, as is likewise the lower front transverse member which joins them. The upper members 2 are preferably made of angle bars and the forward vertical members 4 are also preferably made of angle bars.

The ends of the members 1 and 2 are joined to vertically extending channel members 5, there being two such channel members which are spaced apart and as is shown in Fig. 2, the lower side members 1 are bent inwardly as indicated at 1^a for the purpose of securing them to the channels 5.

The members 1 are provided with transversely extending supporting members one of which is indicated at 6 in Fig. 2.

The space which comprises within the members 1 and 2 and the vertical members 4 is preferably enclosed by a suitable housing of sheet metal such as indicated at 7 and forms a compartment within which is housed a storage battery 8 and a motor 9. The motor 9 in the present instance is mounted so that its shaft extends in a vertical direction, the shaft or an extension thereof, extends beneath the floor of the housing just described, for the purpose of driving the forward truck wheels.

There is secured to the lower portions of the channel members 5 an extending frame which is generally indicated at 10. This frame at one end thereof is secured at the 5 lower end of the channels 5 and the frame comprises rearwardly extending members which converge, these members being indicated at 10^a. At their ends the members 10^a are united to a transversely extending portion 11, which at its outer ends is constructed to have spaced ears between which are pivoted the short axles 12 of the wheels 13. These short axles 12 are pivoted upon the portion 11 just described so as to permit 15 movement of the wheels 13 about their pivotal mounting for the purpose of steering as will later be described.

The channel members 5 are at their upper portions secured to a transversely extending 20 channel member 14.

At the upper ends of the members 5 there are secured extending angle members 16 which are held by means of gusset plates 17. The members 16 support trunnion blocks 18 25 in which a motor 19 is mounted.

Between the front end of the member 2 and the upper portions of the channels 5 there extend diagonal braces 20 which are usually made of angle iron. These braces 30 20 are secured to the upper portions of the channels 5 and are not secured to the gusset plates 17, nor to the extending members 16 which support the motor.

It will be noted that the rear portion of 35 the frame 10 lies below the forward portion of the frame as represented by the side channel members 1.

Below the forward portion of the frame, that is to say, below the side channel members 1, there is a transversely extending axle 40 22. This is shown in Fig. 2. This axle at its outer ends is constructed to receive a knuckle joint generally indicated at 23, which knuckle joint follows the usual construction of carrying a short shaft upon which the wheel, as indicated at 24 is mounted, same construction pertains with respect to wheel 25.

Without entering into any detail description, 50 it may be said that a gear mechanism not shown or described, is provided for driving the wheels 24 and 25, at the same time permitting their being turned for steering purposes.

55 This structure in part is shown in Fig. 1 in which there is shown a gear 26 which meshes with a worm 27 that is carried upon a shaft 28, which shaft is in turn connected with the motor shaft as indicated in 29.

60 Upon shaft 28 there is a drum 30 and cooperating with this drum is a braking mechanism 31 shown in Figs. 1 and 2 the brake mechanism is applied by means of a foot lever 32^a which is pivotally adjacent the 65 front platform 32, this platform being car-

ried by members, which are in turn supported from the transverse channel member 3.

Connected with the axles which support the wheels 24 and 25 are arms 33 and 34. 70 These arms being capable of being turned for the purpose of steering the wheels. The arms 33 and 34 are connected with a member 35 by means of rods 36, shown in Fig. 2. The member 35 is mounted upon a 75 shaft 37 which as shown in Fig. 2 is at its upper end supported in one of the rear cross members such as 6 and at its lower end is supported by a bracket 38 which is carried by the cross channel 39^a, which secures the 80 lower ends of the channels 5 together. The shaft 37 is capable of turning in its bearings.

Upon the shaft 37 below the member 35, there is mounted a member 39 which is provided with arms 40 and 41. To the arms there is secured a rod 42 which at its forward end connects with a bell crank lever 43, which lever is pivoted at its elbow and the bell crank lever in turn is connected 90 with a rod 44, which is pivoted to the arm 45, which arm 45 is pivoted to a portion of the frame of the machine. The arm 45 is provided with ears 45^a between which there is secured a steering arm 46. 95

It will be apparent that in steering the machine, the lever 46 is raised or lowered, in order to steer the machine, toward the left or toward the right.

The member 11 to which the side portions 100 10^a of the rear portion of the frame 10 is connected, is provided with extending arms 11^a. These arms converge and at their point of convergence they give support to a sleeve 48, (see Fig. 3) which carries an arm 49 to 105 which arm there is pivotally secured a rod 50, this rod extends slightly above the frame 10 and at its forward end is secured to the arm 41 which is carried upon the member 39 so that as the member 39 may be turned 110 through the action of the rod 42, motion is imparted to the rod 50.

The sleeve 48 also is provided with an arm 51 and to this arm 51 there are pivoted rods 52 which extend divergently and are pivotally connected with arms 53 which are carried by the short axles for the wheels 13. 115

From the construction which has been described and shown in Fig. 2 it will be seen that the front and rear wheels are steered 120 simultaneously, but the rear wheels are not moved in the same direction as the front wheels, but in the opposite direction. That is to say, when the front wheels are turned about their pivots in a clockwise direction, 125 the rear wheels are turned about their pivots in a counter-clockwise direction.

The controller by which the operation including the starting and stopping of the driving motor 9 is controlled, is indicated 130

at 55. This controller has a portion thereof connected with a rod 56 which in turn is connected with a foot lever 32^a, heretofore described.

5 The purpose of the connection 56 is to move a portion of the controller to make it operative only when the plate 32^a is depressed, in other words, when an operator is standing on the platform 32. As will be 10 noted this plate 32^a also operates the brake 31.

Co-operating with each of the upright channel-members 5 are members 58 which will be more clearly seen in Fig. 5. These 15 members 58 have arms 59 and 60 and the arms 59 adjacent one end thereof have rollers 61, which are mounted upon a shaft 62, which shaft extends transversely between the channel members 5 and the arms 20 on the members 58 receive and journal the shaft 62.

The arms 59 of each of the members 58 support another shaft 63 which is substantially at the juncture of the arm 59 and 25 60. This shaft supports rollers 64, which rollers bear upon the opposite side of the channel members 5 to which the rollers 61 bear, so that there is a cantilever effect. Between the arms 59 there extends a joining member 65 and upon this member there are ears 66, which co-operate with ears 67 which are carried by the arms 59. Each 30 set of ears 66 and 67 forms a support for the trunnions of a nut 68 and each nut 35 operates with threaded members 69 and 70.

The arms 60 extend away from the channel members 5 and between these arms there extends a short shaft 71 to which there 40 are pivoted members 72, which members form supports and extend longitudinally beneath the platform 73.

The outer ends of the arms 60 are provided with set screws 60^a which are adapted to engage with the under side of 45 the platform 73, so as to adjust the platform for the purpose of leveling the same where such may be desired. During these movements as will be understood the platform swings about the shaft 71.

50 The threaded members 69 and 70 are at their lower ends supported in brackets, one of which is indicated at 75 in Fig. 5.

These threaded members extend longitudinally between the members 5 and at 55 their upper ends, the members 60 and 70 extend into a casing 76 which is supported at the upper end of the members 5.

The casing is provided with trunnions 76^a which engage in supports 77. Within 60 the casing 76 there is a worm gear 78 which is secured to the member 69. There is also a worm gear 79 which is secured to the threaded member 70. Both of the gears 78 and 79 mesh with a worm 80 which worm 65 is driven by shaft 81, which through a suit-

able clutch mechanism contained within a housing 82, connects with the shaft of the motor 19.

The construction which has just been described is made quite flexible so that there 70 will be no binding action due to any load, which binding action might tend to render more difficult the driving action of the motor 19 and the transmission of its power to the members 69 and 70.

75 The worm 80 is of such a pitch with respect to the worm gears 78 and 79 that a locking action results, if power be transmitted from the members 69 and 70 to the worm gear 80. This construction prevents 80 the platform from descending under its own weight or load and furthermore, when the platform is raised and the power is shut off, the platform remains at the position to which it has been raised.

85 It will be apparent from the foregoing description that as the motor drives the worm 80 the worm gears 79 and 80 will cause rotation of the members 69 and 70. These members of course, are driven in opposite 90 direction, but they are oppositely threaded, therefore they produce the same resultant effect, so far as the movement is concerned with respect to the nuts 68 which are associated therewith. The nuts traveling along 95 the members 69 and 70 will cause the members 58, which in turn carry the platform, to be raised or lowered in accordance with the direction in which the motor 19 is driven.

100 The motor 19 is electrically connected with the battery 8 and the circuit for the motor is controlled by a controller which is indicated at 84. This controller may be of any suitable type, and is so constructed that when the handle is pulled in a forward 105 direction suitable electrical connections are made to move the platform 73 in one direction and when the handle is pushed in a rearward direction with respect to the operator suitable electrical connections are made 110 to move the platform 73 in the opposite direction.

115 The handle of the controller 84 is by means of a rod 85 connected with an arm of the bell crank lever 86, which bell crank lever is pivoted on the frame of the machine as indicated in Fig. 1. The other arm of the bell crank lever is connected to two rods 87 and 88, which at their extremities are connected to two levers which are indicated at 120 89 and 90 respectively; these levers are pivoted to adjacent portions of the machine, as indicated in Fig. 1.

125 The levers 89 and 90 are so positioned that they lie in the path of movement of the shaft 62 which connects the upper rollers 61 of the platform 73.

The handle to the controller 84 is pushed rearwardly with respect to the operator when the elevating platform 73 is raised. 130

Movement of the handle of the controller in the manner indicated causes the rod 87 to be drawn downwardly so that the lever 89 is moved downwardly about its pivot. 5 As the platform 73 is elevated and reaches a position at substantially the highest position to which it is desirable to have the platform ascend, the shaft 62 engages with the lever 89, raising the lever and thereby, 10 through the mechanism which connects it with the handle of the controller, moving the controller to its neutral position. This, then, breaks the circuit between the motor 19 and the battery, thereby stopping the 15 driving action of that motor.

When the platform is to be lowered the handle of the controller 84 is moved in a forward direction with respect to the operator, which in turn causes the rod 88 to 20 be elevated and by so much the lever 90 to be elevated. Therefore, when the raising platform 73 descends to a place adjacent its lowermost position the shaft 62 which carries the roller 61 engages with the lever 90, 25 depressing the same and moving the controller handle to its neutral position, thus disconnecting the motor 19 from the battery 8.

It will, therefore, be apparent that the 30 mechanism which has just been described forms a pair of limiting stops which effectively arrests the driving action of the motor with respect to the platform 73 when the table has reached its uppermost or its 35 lowermost position.

As a matter of safety it is very desirable that the motor 9 which is the propelling motor for the truck itself shall not be operated nor capable of operation during the 40 raising and lowering of the platform 73. The reason for this is almost obvious, as it will at once be apparent that when the platform 73 is raised to a height of a few feet above the floor, particularly when the platform carries a load, it is dangerous to have 45 the truck in movement.

On the other hand there may be a limited amount of movement of the platform 73 permitted when the platform is near its 50 lowermost position. Under such circumstances even if the platform 73 carries a load it is so near the floor, or in other words, the center of gravity of the platform and its load is so low that there could be no tipping action possible.

I have, therefore provided a construction such that the platform 73 may be raised or lowered to a limited extent when near its lowermost position, but when the platform 60 is raised to the higher positions, the circuit which includes the motor 9, the battery 8, and the controller 55, is opened, rendering that circuit dead so that the motor 9 can not be operated.

65 The permissible height to which the table

73 may be raised before the circuit just mentioned is broken is of course arbitrarily fixed in the machine, and in the present instance the construction is such that the platform 73 may be raised or lowered within approximately a distance of 10" from the floor without opening the circuit to the driving motor 9.

The construction by which this is effected is more particularly shown in Fig. 5.

One of the channels 5 carries a pair of contacts indicated at 90 and 91. These contacts are spaced apart. A lever 92 is pivoted at 93 upon the channel 5. This lever carries an arm 94 which is pivoted upon the lever 92 above the pivot 93. The lever 92 carries a second arm 95 which is pivoted to the lever 92 below the pivot 93. Both the arms 94 and 95 are mounted so as to extend through a portion of the channel 5 into the path of movement of one of the rollers 61. The lever 92 at its upper end carries a block of conducting material which is indicated at 96. When the block 96 engages with the contacts 90 and 91 the circuit of which the contacts 90 and 91 are a part is closed, and when the lever 92 is moved so that the block 96 is disengaged from the contacts 90 and 91 the circuit of which these contacts are a part is open. As shown in Fig. 5, the roller 61 is below the arm 94. Therefore the platform 73 may be raised or lowered a limited extent without engaging the arm 94 and so long as the movement of the platform 73 is confined within the limits just specified the circuit of which the contacts 90 and 91 is a part is closed.

In Fig. 6 there is shown a diagram illustrating the circuit which includes the battery 8, the motor 9 and the controller 55, and the contacts 90 and 91 form parts of this circuit.

Therefore it will be seen that when the circuit between the contacts 90 and 91 is closed, as I have above explained, the motor 9 may be operated so that the truck may be moved and the platform 73 may be raised or lowered within the limits set forth. When the platform 73 is elevated so that the roller 61 engages with the arm 94, it depresses the arm 94 thereby moving the lever 92 about its pivot and breaking the electrical connection between the contacts 90-91. This, as will be clear, opens the circuit between the battery and the motor 9. Therefore in all positions of the raising platform 73 above the position in which the roller 61 engages the arm 94, the circuit to the motor 9 is open, and therefore the truck can not be driven.

It will be clear that if the roller 61 has engaged and pushed the arm 94 inwardly, as the platform 73 is raised, the lever 95 has been pushed outwardly and is in position to be engaged by the roller 61 upon the de-

scent of the table 93. When the roller engages the arm 95 it pushes it inwardly thereby moving the lever 92 into position to close the circuit between the contacts 90 5 and 91.

The construction which has just been described enables the device to be used as industrial lift trucks are normally used, that is to say, providing the raising and lowering platform with but a limited range of movement, or the device may be used as a tiering device because it will be apparent the platform 73 may be raised to any desired height within the limits of the construction 10 of the machine. Therefore the device may be used in connection with the usual type of load carrying skids, being operated so as to insert the platform 73 beneath the same, after which the platform may be 15 raised a limited amount just sufficient to raise the skid off the floor and the load be transmitted in this condition, or where it be desired to tier the load carried, the platform 73 may be raised to any desired height 20 within the limits of the machine.

In operating the machine the operator usually faces the raising platform and the forward movement is usually made with the platform ahead. However, it is not intended by any statement herein to in any 30 way to limit the invention as to which may be considered the front or the rear end of the truck.

Having described my invention, I claim, 35 1. In a truck, a frame, wheels upon which the frame is mounted, said frame having a rear portion which is low lying and adjacent to the supporting surface for the truck, substantially vertically extending members 40 which are carried by the frame and adjacent one end of the rear portion of the truck frame, a platform mounted to move upon the said vertical members and guided thereby and means for raising and lowering the 45 platform.

2. In a truck, a frame, wheels upon which the frame is mounted, means carried by the frame for driving the truck, said frame comprising a front elevated portion and a 50 rear low lying portion, vertically extending members carried by the said frame at the adjacent ends of the said portions of the frame, a platform mounted to move upon the said vertical members and guided thereby and means for raising and lowering the platform.

3. In a truck, a frame, wheels upon which the frame is mounted, means carried by the frame for driving the truck, said 60 frame comprising a front elevated portion and a rear low lying portion, vertically extending members which join the adjacent end portions of the elevated and low lying portions of the frame, a platform mounted to move upon the said vertical members

and guided thereby and means for raising and lowering the platform.

4. In a truck, a frame, wheels upon which the frame is mounted, means carried by the frame for driving the truck, said frame 70 comprising a front elevated portion and a rear low lying portion, vertically extending members which serve to join the two adjacent portions of the frame, said vertical members extending above the elevated portion of the frame, a platform mounted to move upon said vertical members and serving to guide the platform and means for raising and lowering the platform.

5. In a truck, a frame, wheels upon which the frame is mounted, means carried by the frame for driving the truck, oppositely disposed vertically extending members secured to the frame, a platform mounted to move upon the said vertical members and 85 guided thereby, a supporting means mounted adjacent the upper end of said vertical members a motor supported upon the said supporting means, operating mechanism for raising and lowering the platform and a 90 connection between the motor and operating means.

6. In a truck, a frame, wheels upon which the frame is mounted, means carried by the frame for driving the truck, said frame comprising a front elevated portion and a rear low lying portion, vertically extending members which serve to join two adjacent portions of the frame, said vertical members extending above the elevated portion of the 95 frame, a motor supported by and at the upper end of said vertically extending member, a movable platform mounted to move upon said vertical members, operating mechanism for raising and lowering the 100 platform and a connection between the motor and said operating mechanism.

7. In a truck, a frame, wheels upon which the frame is mounted, means carried by the frame for driving the truck, oppositely 110 disposed vertically extending members secured to the frame, a platform associated with the vertically extending members and guided thereby, a threaded member extending means and a driving connection between 115 vertical members, a nut cooperating with said threaded member, said nut being carried by the platform, a supporting means mounted adjacent to the upper end of the vertical members, a motor carried by said supporting means and a driving connection between 120 the motor and the said threaded member.

8. In a truck, a frame, wheels upon which the frame is mounted, means carried by the frame for driving the truck, oppositely disposed vertically extending members secured to the frame, a platform mounted to move upon the said vertically extending members, a plurality of threaded members extending longitudinally with respect to the vertical 130

- members, a nut cooperating with each threaded member, each of said nuts being connected with said platform, worm wheels mounted at the ends of said threaded members, a driving worm cooperating with said worm wheels, a motor supported adjacent to said driving worm and a driving connection between the motor and said driving worm.
9. In a truck, a frame, wheels upon which the frame is mounted, means carried by the frame for driving the truck, oppositely disposed vertically extending members secured to the frame at points midway between the ends thereof, a platform mounted to move upon the said vertically extending members, a threaded member extending longitudinally and between the said vertical members, a nut associated with the platform and cooperating with the said threaded member, a worm wheel mounted at one end of the said threaded member, a driving worm cooperating with said worm wheel, a motor supported adjacent to said driving worm and a driving connection between the motor and said driving worm.
10. In a truck, a frame, wheels upon which the frame is mounted, means carried by the frame for driving the truck, oppositely disposed vertically extending members secured to the frame, a platform mounted to move upon said vertical members and guided thereby, a plurality of threaded members extending longitudinally with respect to the vertical members, a nut associated with each threaded member, said nuts being connected with the said platform, a worm wheel carried by each threaded member adjacent to an end thereof, a driving worm cooperating with said worm wheel, a support secured to said vertical members adjacent the ends thereof, a motor carried by said support, and a driving connection between the motor and the said driving worm.
11. In a truck, a frame, wheels upon which the frame is mounted, means carried by the frame for driving the truck, oppositely disposed vertically extending members secured to the frame, a platform mounted to move upon said vertical members and guided thereby, a nut associated with each of the threaded members, said nuts being connected with the platform, a casing pivotally mounted at its ends adjacent the ends of the said vertical members, worm wheels within said casing, each worm being connected with one of the said threaded members, a driving worm supported in the casing and cooperating with the said worm wheels, a support adjacent the upper ends of said vertical members, a motor pivotally supported upon said support, and a flexible driving connection between said motor and the said driving worm.
12. In a truck, a frame, wheels upon which the said frame is mounted, a pair of vertically extending members, a platform, said platform being guided and retained by the said vertical members, a pair of threaded members which extend longitudinally between the said vertical members, said members being oppositely threaded, a nut associated with each of the said threaded members the said nuts being carried by the platform, worm wheels connected with the upper ends of each of said threaded members, a driving worm engaging with the worm wheels, the pitch of said worm with respect to the said worm wheels being such that the worm wheels cannot drive the worm, a motor mounted adjacent the upper end of said vertical members and a driving connection between the motor and the driving worm.
13. In a truck, a frame, wheels upon which the said frame is mounted, a pair of vertically extending members, a platform, said platform being provided with rollers which lie upon opposite sides of the said upright members whereby the platform is guided and held in its movement, a pair of threaded members extending longitudinally between the said vertical members, a nut associated with each of the said threaded members, the said nut being mounted upon the platform, a worm wheel associated with an end of each of said threaded members a worm cooperating with the said worm wheels for driving the same and means for driving the said worm.
14. In a truck, a frame, a pair of vertically extending members, a platform support, said platform support adjacent one end being provided with rollers which bear upon opposite sides of each of the said vertical members whereby the said support is guided and held in its movement, a platform pivoted upon such support and sustained by the said support, and means for raising and lowering the said support.
15. In a truck, a frame, a pair of vertically extending members and support, said support being provided with means which engage upon opposite sides of the vertical members whereby the support is guided and held in its movement, a platform pivoted at one end upon said support and means for engaging another part of the platform whereby the platform may be adjusted with respect to its support and means for raising and lowering the said support.
16. In a truck, a frame, a platform, means for raising and lowering said platform including a motor and controller for the said motor and mechanically operated stops arranged at the upper and lower limits of movement of the platform, means carried by the platform for operating said stops and means connecting the said stops with the controller whereby when the stops are

operated the controller is thrown into neutral position.

17. In a truck, a frame, a platform, means for raising and lowering said platform including a motor and controller for the said motor a movable member mounted adjacent the upper limit of movement of said platform and a movable member mounted adjacent the lower limit of movement of said platform, means connecting each of said movable members with the controller whereby the controller is moved to neutral position when the platform engages with either of the movable members.

18. In a truck, a frame, a platform, means for raising and lowering said platform including a motor and controller for said motor and a movable member mounted adjacent the upper limit of movement of the platform, a movable member mounted adjacent the lower limit of movement of the platform, rods associated with said movable members and a lever with which said rods are connected and a rod connecting the lever with a moving part of the controller for the purpose specified.

19. In a truck, a frame, a pair of vertically extending members, a platform, said platform being guided and retained by said vertical members, means for raising and lowering said platform, said means including a motor and a movable member mounted adjacent the upper end of said vertical members, a movable member mounted adjacent the lower end of said vertical members, said movable members lying in the path of movement of a part of the platform, a controller for said motor and means connecting the said movable members with a movable part of the controller whereby the controller is moved to neutral position when the platform engages the movable member at the top or at the bottom of the vertical members.

20. In a truck, a frame, wheels upon which the said frame is mounted, a motor mounted upon the said frame for driving the truck, a movable platform, means for raising and lowering said platform, a switch, said switch comprising a stationary part and a movable part, said switch being electrically connected with the motor, said

platform being adapted to operate the movable part of the switch during its elevating or lowering movement.

21. In a truck, a frame, wheels upon which a frame is mounted, a motor carried by the frame for driving the truck, a platform, means for raising and lowering the platform, a switch comprising a stationary part and a movable part, a pair of operating members connected with the movable part of the switch which operating members lie in the path of movement of a portion of the platform whereby the switch will be operated by the raising and lowering movement of the platform.

22. In a truck, a frame, wheels upon which the frame is mounted, a motor carried by the frame for driving the truck and raising and lowering platform guiding means with which the platform cooperates, means for raising and lowering the platform, a switch member comprising a movable member and a stationary member which switch is electrically connected with the motor, operating members associated with the movable part of the switch, which movable members are also associated with the said guiding members and in position to be engaged by a portion of the platform upon the raising and lowering thereof thereby to move the switch into open or closed position.

23. In a truck, a frame, wheels upon which the frame is mounted, a motor carried by the frame for driving the truck, vertically extending members, a platform having rollers associated therewith which engage with the said vertical members, means for raising and lowering the said platform, a switch for controlling operation of the motor comprising a movable member and a stationary member associated with one of the vertical members, operating means for said movable member carried by one of the vertical members and extending in the path travel of a platform roller whereby the movable member of the switch is moved to open or closed position as the platform ascends or descends.

In testimony whereof, I hereunto affix my signature.

HENRY T. PLEINES.

Certificate of Correction.

It is hereby certified that in Letters Patent No. 1,432,299, granted October 17, 1922, upon the application of Henry T. Pleines, of Cleveland, Ohio, for an improvement in "Industrial Trucks," an error appears in the printed specification requiring correction as follows: Page 5, line 115, claim 7, strike out the words "means and a driving connection between" and insert the words and syllable *longitudinally with respect to the verti-*; and that the said Letters Patent should be read with this correction therein that the same may conform to the record of the case in the Patent Office.

Signed and sealed this 9th day of January, A. D., 1923.

[**SEAL.**]

KARL FENNING,
Acting Commissioner of Patents.
